UNITED STATES PATENT OFFICE.

GUSTAV P. HELFRICH, OF NEW YORK, N. Y.

TUNNEL CONSTRUCTION.

1,363,115.

Specification of Letters Patent. Patented Dec. 21, 1920.

Application filed October 30, 1919. Serial No. 334,517.

To all whom it may concern:

Be it known that I, GUSTAV P. HELFRICH, a citizen of the United States, and a resident of the city of New York, borough of the Bronx, in the county of Bronx and State of New York, have invented a new and useful Tunnel Construction, of which the following is a full, clear, and exact description.

10 This invention relates to tunnel construction, and particularly to tunnels which are made at one place and moved into their fixed position, and has for an object to provide a construction which may be moved 15 gradually from one or both shores into position on or beneath a river bed.

Another object is to provide a tunnel structure which is capable of manufacture on the shore and then present a structure where- 20 in it may be easily pulled or pushed into position especially provided in a river bed.

A still further object is to provide a tunnel structure made substantially in sections, formed to be almost as buoyant as water, 25 whereby they may be easily shifted from a land position to a submerged position at any point along the river bed, the various sections being connected immediately before they enter the water in order to produce a 30 continuous tunnel or tube formation.

In the accompanying drawings:

Figure 1 is a sectional view indicating a river and an embodiment of the invention shown in connection therewith, the same being in the course of construction.

Fig. 2 is a sectional view through Fig. 1 on line 2—2, the same being on a greatly enlarged scale.

Fig. 3 is a fragmentary side view on an 40 enlarged scale, showing the connection between the sections illustrated in Fig. 1.

Fig. 4 is a fragmentary horizontal sectional view through Fig. 2 on line 4—4.

Fig. 5 is a view similar to Fig. 1, but dis- 45 closing a slightly modified form of the invention wherein the tunnel sections are moved toward the center of a river from each bank thereof.

Fig. 6 is a fragmentary longitudinal ver- 50 tical section showing adjacent sections of a tunnel immediately before interlocking.

Fig. 7 is a sectional view through Fig. 5 on line 7—7, the same being on an enlarged scale.

55 Referring to the accompanying drawings by numerals, 1 indicates a river bed which

has been dug out at 2 to produce a trans- 60 verse channel or gutter in which the tunnel is to be placed. This excavation may be shallow or comparatively deep as desired. 65 As shown in Figs. 1, 5 and 7 the excavation is substantially half as deep as the tunnel structure, but it may be sufficiently deep to cause the tunnel structure to be flush with the river bed and thereby obviate any pro- 70 jections or any abutment against which the water or silt may operate. However, the depth at which the tunnel may be laid may be varied widely without departing from the invention. As shown in Fig. 1 a num- 75 ber of sections 3 have been provided, these sections being constructed on what may be termed a skid 4 arranged on the land ad- 80 jacent the shore line of the river. As the sections are built up they are pulled, or if desired pushed, into the river. These sec- 85 tions may be of any length, as for instance one hundred or two hundred feet, and are of the proper weight to be almost as buoy- 90 ant as water, so that when pulled into the river there will be but little friction between the section and the ground, thus permitting an easy shifting or movement of the entire tunnel structure. The power for shift- 95 ing the tunnel structure may be tugs where the river is comparatively wide, or may be one or more cables 5 connected with a windlass 6.

As shown in Fig. 1, the structure is de- 90 signed to be manufactured on one side of a river and drawn gradually across the river to the opposite side. To accomplish this re- 95 sult and secure the buoyant effect of the sections a bulkhead 7 is provided in the front end of the first section, while all the rear 95 sections are open to each other and to the air at the shore end. Each of the sections 3 is made up of a number of rings 8 of metal, illustrated in Figs. 3 and 4, each of said rings having inturned annular flanges 9 and 10, which are suitably riveted together. The rings 8 form an outer metal casing, said rings being open or cut away at 11, as shown in Fig. 7. An inner shell formed of rings 12 is also provided, said inner ring being 105 open at the bottom or at point 13. Each of the inner rings is provided with outwardly extending flanges 14 and 15 designed to be connected by rivets, or otherwise as desired. These rings are held spaced apart by suit- 110 able bracing bars 16, held in place in any suitable manner, as for instance by being

riveted in place. The various rings forming the sections 3 are riveted together while on the skid 4 and are moved gradually into the water, and as the sections move into the water a bed 17 of concrete is provided, which may be provided with suitable openings 18 for electric wires, water, gas, or other things. A sufficient amount of concrete is provided to not only close the opening 13 in the inner 10 casing, but to cause the section to sink in the water. As the section moves farther and farther into the water additional concrete must be provided so that it will always be slightly heavier than the water. When a 15 sufficient number of sections have been constructed and moved out some distance into the water, additional concrete is placed between the inner and outer shells, and also the opening 11 is filled with concrete. This 20 completes the immediate construction of the tunnel sections, but usually an additional supply of concrete 19 is provided, as shown in Fig. 7, to reinforce and properly weight the entire structure, which can be put down 25 after the tunnel is in final position.

From Figs. 1 and 2 it will be seen that the skid is made up of a number of wheels 20, supported by a number of shafts 21, each shaft being carried by a pair of adjustable 30 jacks 22 so that the sections may slide properly into the water.

The construction shown in Fig. 1 is intended to be manufactured on one side of the river and drawn gradually across until the 35 entire tunnel structure is properly located. If desired, and where the river is comparatively wide the various sections 3 are manufactured on both sides of the river and drawn toward the center, where they are caused to slightly telescope or overlap as indicated in Fig. 6. It will be seen that several rings 24 and 25 are provided on the ends 40 of the adjacent sections. The ring 25 is slightly smaller than the ring 24 and thereby 45 slidingly fits within ring 24, and a supply of cement or concrete may be deposited on the exterior thereof for insuring a solid or water-tight connection. After the parts have been 50 properly connected the bulk-heads 26 and 27 are removed and the interior part of the tunnel finished in any desired manner.

In Fig. 5 a further form of the invention is shown wherein the various sections 3 have 55 been manufactured on opposite sides of the river and drawn into the river, though not in contact. This is where the river is very wide, and consequently it would be very difficult to pull the sections to a central point. In a case of this kind the sections are drawn 60 in toward the center as far as possible with the bulk-heads 28 and 29 in position. A number of central sections 30 are then built in any desired manner, as for instance built on the shore, floated to the place where they 65 are to be located and then lowered. After

the central sections 30 have been placed in position, or formed in any desired manner, the bulk-heads 28 and 29 are removed and the tunnel properly finished interiorly, and if desired finished exteriorly by an extra deposit of concrete, as shown in Fig. 7. The center section of the tunnel could also be completed by placing two pneumatic shields, one in the front part of each of the two side sections before the tunnel is started, and 70 after the two side sections are in position, the bulk-heads could be removed and the tunnel finished by the pneumatic process now in common use. In some instances the river bed is not sufficiently strong to support the weight of the tunnel and in cases of this kind a number of piles 31 are provided at the desired point and a bed of cement 32 placed thereon. If desired the bed of cement 32 could be joined with the cement 19 and 80 produce a thorough support and anchor.

It will, of course, be understood that the ends of the tunnel may be connected up with suitable terminals in any desired manner without departing from the spirit of the 90 invention, and also that the tunnel may be used for railways or as a vehicular tunnel, water, oil or gas conduits, or for other purposes.

Primarily the construction is especially 95 adapted for use in tunnels under water, but the same general construction of casing could be used where a tunnel is positioned on land. The construction could be built in correct position originally, or could be built and 100 moved along the ground to a limited extent.

While only a tunnel circular in cross section has been shown it is evident that the tunnel could be built square, elliptical, or other shape in cross section without departing 105 from the invention. It will also be evident that additional bracing or reinforcing members or structures could be used if desired in addition to the bracing or reinforcing action of the flanges 9 and 14.

In actually constructing at any particular point a tunnel embodying the invention a number of slight variations may be utilized as may be desired. For instance when a tunnel is to be pushed or pulled all the way 115 across a water way the front part is built as a mere shell for a distance usually equal to the height of the tunnel provided by the concrete. If the tunnel was built complete it might be entirely too heavy to be pulled up 120 on the other side of the water way. Where the tunnel is formed in this way it is weighted down with a material of any kind, as for instance sand or gravel, sufficiently to keep it down as it is moved across a water way and afterward said material is removed before the front end is pulled up on to the shore. In addition the prepared groove or ditch 2 may be of various contours, but preferably where the tunnel is to be pulled en- 125

tirely across a water way, as shown in Fig. 1, said ditch is substantially arc-shaped, while the same shape may be used when the parts are arranged as shown in Fig. 5 on 5 the other sections of the ditch, and consequently the tunnel may be in a straight line at an incline until it reaches the central section which is preferably level. Where the two ends are pulled from the opposite shores 10 and are telescoped as shown in Fig. 6, the sections are perfectly straight, something on the order of a flat V-shaped arrangement and the overlapping members fitted to properly telescope.

15 What I claim is:

1. The method of constructing and positioning tunnels comprising the formation and assembling of a plurality of tunnel sections on land with sufficient buoyancy to 20 barely sink when placed in water, positioning a bulk-head in the first section to enter the water, moving said sections across a body of water so that a series of connected sections will be positioned end for end on 25 the bottom of said body of water, and then applying a covering of concrete to said sections.

2. A tunnel comprising a plurality of sections formed with an inner and outer shell, 30 the inner shell being open at the bottom and

the outer shell being open at the top, means connecting the respective sections, and a filling arranged between said shells.

3. A tunnel construction of the character described comprising a plurality of sections, 35 each section being formed with an outer tubular metal shell having an open section extending longitudinally along the top, an inner metal tubular shell having an opening extending longitudinally at the bottom, and 40 a filling arranged between said shells.

4. The method of constructing and positioning tunnels comprising the formation of tunnel sections on land with ballast permitting a sufficient buoyancy to barely sink 45 when placed in water, assembling the sections immediately previous to their entrance into the water, positioning a bulk head in the first section to enter the water immediately previous to its entrance, pulling said 50 sections into and across the water so that a series of connected sections will be positioned end for end in a body of water, removing some of the ballast from the end sections as they emerge from the water on 55 the side of the water opposite to their entrance, and then applying a covering of concrete to said connected sections.

GUSTAV P. HELFRICH.
